UNITED STATES PATENT OFFICE

HARRY RODSTEIN AND ISIDORE NATHANSON, OF BROOKLYN, NEW YORK

CURTAIN-RETAINING DEVICE

Application filed May 16, 1930. Serial No. 452,824.

This invention relates to door or window casing attachment holders for retaining curtains, draperies and the like, hanging in the openings of said casings drawn aside or 5 parted.

Among the objects of the invention is to generally improve devices of the character described comprising few and simple parts, which shall be readily assembled to form a 10 rugged yet neat appearing structure, which shall be easy to attach to building structures by persons mechanically unskilled, which shall be simple to operate, cheap to manufacture, and practical and efficient to a high 15 degree in use.

Other objects of this invention will in part be obvious and in part hereinafter pointed out.

The invention accordingly consists in the 20 features of construction, combinations of elements and arrangement of parts which will be exemplified in the constructions hereinafter described and of the scope of application will be indicated in the following claims.

25 In the accompanying drawing, in which is shown various possible illustrative embodiments of this invention.

Fig. 1 is a fragmentary perspective view showing a window casing and curtain retained in drawn aside position by a holder embodying the invention.

Fig. 2 is a front elevational view of the 35 improved curtain holder shown with the arm retained in its ineffective position, said arm being shown in its effective position in dot and dash lines.

Fig. 3 is a cross-sectional view taken on lines 3—3 in Fig. 2.

Figs. 4 and 5 are fragmentary front and 40 side elevational views of a modified construction of the improved curtain holder.

Fig. 6 is a cross-sectional view corresponding to a cut taken on lines 6—6 in Fig. 4, and

45 Fig. 7 is a sectional view showing still another modified construction of improved curtain holder.

Referring in detail to the drawing, 10 denotes a holder embodying the invention for retaining a curtain C drawn aside from an opening O of a window casing W, said holder

10 being attached in any suitable manner to an upright portion of the casing W at a convenient and desirable level, as shown in Fig. 1.

The holder 10 may be made of sheet metal stampings and is seen to comprise a backing plate 11, and an arm 12 swingably mounted thereon. The plate 11, has upstanding from a mid-portion, a boss 11a which forms a bearing against which said arm 12 is mounted adjacent one end 12a thereof. A rivet 13 on which said arm is pivoted, secures the latter to the boss 11a. For limiting the swinging the arm 12 and for retaining the latter rigidly in its effective horizontally extending position, shown in Fig. 1, an edge portion 11b of the plate 11 is bent to overstand therefrom in the path of movement of said arm to serve as a stop against which the arm end 12a abuts.

Spaced from said stop 11b and boss 11a, a protuberance 11c is provided on said plate 11 adapted to frictionally contact with arm end 12a for releasably retaining the arm 12 in its ineffective vertically extending position, shown in full lines in Fig. 2.

The plate 11 may also be provided with spaced holes 11d for receiving suitable fasteners such as nails (not shown), said holes 11d being preferably positioned to facilitate the application of the fasteners for attaching of the device 10 to the casing W.

The application of the invention will now be apparent. The plate 11 and arm 12 are assembled as shown in Figs. 2 and 3, and the device 10 is installed on the window casing W as shown in Fig. 1. When the device 10 is not in use, the arm 12 is swung into the vertical position shown in Fig. 2 with the arm end 12a engaging the protuberance 11c for frictionally retaining same.

To make the device effective, the arm 12 is swung down into its horizontally extending position and the curtain C is drawn aside and retained thereby as shown in Fig. 1. The free end 12b of the arm is preferably offset, as for example, by being curved for forming an obstruction to prevent the curtain from being easily displaced from the arm 12.

In Figs. 4, 5 and 6, a modified construction of the invention is shown. Here the curtain holder 110 has an eyelet rivet 113 in place of the solid rivet 13 used in the device 10 described above to permit insertion of a screw fastener 114 therein. In order to anchor the backing plate 111 against rotation, a suitable piercing prong 112 is formed from the material of the plate 111, as for example, from the lower end of the edge portion 111b serving as the stop.

Instead of using an individual eyelet rivet 113 shown in Figs. 4, 5 and 6, if desired, the said rivet may be made integral with the base 15 111a as shown at 213 in Fig. 7.

The curtain holders shown in Figs. 4 to 7, inclusive, operate in the same manner as device 10 described above.

It will thus be seen that there is provided 20 devices in which the several objects of this invention are achieved and which is well adapted to meet the conditions of practical use.

As various possible embodiments might be made of the above invention, and as various 25 changes might be made in the embodiment above set forth, it is to be understood that all matter herein set forth or shown in the accompanying drawing is to be interpreted as illustrative and not in a limiting sense.

Having thus described our invention, we 30 claim as new and desire to secure by Letters Patent:

1. A device of the character described comprising a base plate, and arm having one end 35 pivotally secured to said plate, and a plurality of members projecting from said plate, one of said members extending from one side of the plate in the path of movement of said end for limiting the swinging of the arm, the other 40 member extending from the other side of said plate formed with a piercing prong to serve as an attachment means.

2. A device of the character described 45 comprising a base plate, an arm, an eyelet rivet extending from one side of said plate for pivotally securing thereto said arm adjacent one end thereof, means adjacent said rivet for frictionally engaging said arm to retain the latter in an inoperative position, means for engaging said arm end for rigidly retaining the arm in an effective position, and means projecting from the other side of said plate for attaching the device to a support.

3. The device set forth in claim 2 in which 50 said rivet, frictional engagement and retaining means form integral parts of said base plate.

4. A device of the character described 55 comprising a backing plate, a boss upstanding from a mid-portion of said plate forming a bearing, an arm having one end pivotally secured against said boss, a projecting stop extending from one side of said plate adjacent

said boss in the path of movement of said end for limiting the swinging of the arm in one direction, a frictional abutment extending from said plate spaced from said boss and stop for releasably retaining the arm to extend in another direction, and a piercing prong extending from the other side of said plate.

5. A device of the character described comprising a backing plate, a boss upstanding 75 from a mid-portion of one side of said plate forming a bearing, an arm, an eyelet rivet extending from said boss pivotally securing said arm thereto adjacent one end thereof, means adjacent said rivet for frictionally engaging said arm to retain the latter in an inoperative position on said plate, means for engaging said arm end for rigidly retaining the arm in an effective position, and means projecting from the other side of said plate for attaching the device to a support.

6. A device of the character described comprising a backing plate, a boss upstanding 90 from a mid-portion of said plate forming a bearing, an arm having one end pivotally secured against said boss, a projecting stop extending from the plate adjacent said boss in the path of movement of said arm for engaging the extremity of said end to limit the swinging movement of the arm in one direction, and a single frictional abutment extending from said plate spaced from said boss and stop for engaging the extremity of 95 said end to releasably retain the arm extending in another direction.

In testimony whereof we affix our signatures.

HARRY RODSTEIN.
ISIDORE NATHANSON.
